Wilmington, Del., a corporation of Delaware

Application November 23, 1949, Serial No. 129,148

18 Claims. (Cl. 28—38)

1

This invention relates to winding machines of the type which comprise a pressure member such as a roll which bears against the surface of the windings to compact the same. More particularly the invention relates to the positive separation of the pressure member or roll from the surface of the windings when the member carrying the windings is decelerated or stopped. The positive separation is synchronized with the brake or braking action applied to the member carrying the windings.

In standard machines for winding yarn, fabrics, films, and the like on a carrying member, such as a cylindrical or conical core, it is usually customary to employ a pressure member such as a roll or roller to compact and smooth out the wound material. Either the carrying member or the pressure member or both may be positively driven. Usually, however, the carrying roll is rotatably mounted in fixed position and driven while the pressure roll is rotatably mounted and movably supported and rests against the surface of the windings on the carrying roll. In such a mechanism, it is difficult to brake the carrying roll without damage to the material thereon because the rate of deceleration of the carrying roll is continuously changing while the deceleration of the pressure roll remains constant and consequently the material being wound is rubbed and damaged by the pressure roll.

In cases where both members are driven, i. e., the carrying and pressure members, complicated devices must be employed to synchronize the revolutions of the same since the peripheral speed of the carrying member and the surface speed of the pressure roll must remain the same. Complicated devices are likewise needed in such a case to synchronize the braking action of the two members in order to avoid damage to the windings due to friction.

In the winding operation irregularities in the windings very often occur due to eccentricities, bulges, or bumps that are formed due to, for example, overly thick portions in the material being wound. Winding devices of the prior art have the disadvantage that if a slight distortion at some part of the periphery of the winding occurs, such as a bulge, the pressure element is moved outwardly from the axis of the winding at the position of the bulge and then returns toward the axis of the winding as it leaves the bulge causing a bumping of the pressure member on the surface of the windings each time the bulge is contacted. During high speed winding, the fluctuations of the pressure elements

2

that result from hitting one or more of such bulges about the periphery, tends to cause "chattering" or vibration and an unsatisfactory winding results, i. e. one not having a round cross section. There is also the danger that the bouncing or vibration of the pressure member or roll on the surface of the windings will damage the same.

Accordingly, it is an object of the present invention to overcome the aforementioned difficulties and provide a simple means for preventing damage to the windings during the braking of the member carrying the same.

Another object of the present invention is to provide a simple and efficient means for removing the pressure member from the carrying member surface during the braking of the latter.

Another object of the invention is to provide an apparatus for producing a perfectly round section winding containing windings having a minimum of abraded portions.

Other advantages and objects of the present invention will be obvious from the drawing and description thereof hereinafter.

In the drawing, which is intended to be illustrative and not limitative,

Figure 1 is a side elevation of one embodiment of the invention,

Figure 2 is a side elevation of another embodiment of the invention,

Figure 3 is a plan view of the snubbing mechanism, and

Figure 4 is a diagrammatic view of an electrical system that may be employed with the embodiments shown in Figures 1 and 2.

The objects of this invention are in general accomplished by providing a rotatably mounted pressure roll which rests against the surface of the positively driven winding roll. This pressure roll may be made of aluminum, phenolite, rubber, neoprene, and the like, or its outer surface may be covered with a layer of one of these materials. The winding roll is provided with a brake or, if desired, both the winding and pressure rolls may be provided with brakes.

The pressure roll supporting assembly is movably mounted such that the pressure roll may be moved by the winding roll as the material builds up thereon. The pressure roll assembly is also provided with means to prevent its return toward the winding roll when once displaced. However, means are provided to return the pressure roll assembly to its starting position when a new winding is started.

The pressure roll is movably mounted on the

movable assembly so as to be capable of being removed from the surface of the winding roll independently of the pressure roll assembly by positive removing means such as a torque motor and cable, solenoids, and the like. In this case, however, the pressure roll is returned to the winding roll surface when releasing the positive removing means. The positive pressure roll removing means and the winding roll braking means are synchronized so that the pressure roll is removed from the winding roll surface substantially before the deceleration is completed and preferably before the latter begins to decelerate.

The apparatus may be adjusted so that the pressure roll may be retracted or removed any reasonable distance such as $\frac{3}{2}$ inch, prior to braking the winding roll.

For a more detailed description of the invention, reference is made to Figure 1 of the drawing which depicts one embodiment of the invention as it is applied in winding yarn on a warp beam. It should be understood that while the invention is described with respect to its application to a warp beamer, this is merely intended to be illustrative and in no sense limitative.

The yarn 1 coming from the creel (not shown) passes over a guide A, under the hook-like portion of the dropwire-switch 4, through openings in an eye-board 2, between the guides B and C which serve to converge the various yarns in a plane, then through a comb 3, over a guide or measuring-roll 4a, and then wound on the beam 5. The beam is driven by means of the belt 6 attached to the power or driving motor 7.

Resting against the surface of the beam is a pressure roll 8, shown in the raised position, the dotted lines representing the lowered or normal position. The pressure roll is rotatably mounted on shaft 8a which is supported at either end of the pressure roll by lever arms 10 pivotally mounted on shaft 9. A link or arm 11 is rigidly attached or keyed to shaft 9 and extends downwardly away from the pressure roll. Extending outwardly from link 11 and forming an integral part thereof, is a sector gear 11a. The other end of link 11 is pivotally mounted on the transverse shaft 12 attached to the frame of the machine. Also locked to the shaft 9 by means of the key 13 is an upwardly extending arm or link 14. Links 11 and 14 are fixed relative to each other and, if desired, may be one integral link or arm. It is, of course, to be understood that if desired the same mechanism may be duplicated on the other side of the machine.

Toggle links 15 and 15a connect the arms 10 and 14. Extending between the center joint 16 of the toggle linkage and the arm 10 is a tension spring 17 which, when the pressure roll is in contact with the surface of the beam, holds the toggle linkage in the dotted line position 15b against the toggle link stops 18 positioned on the sides of arms 10 and 14. In this normal or rest position 15b against the toggle link stops 18, the center joint 16 is positioned slightly off center or below a line drawn between pivotal points 19 and 20 on arms 14 and 10 respectively. Thus, when the pressure roll and arm 10 move in a counter-clockwise direction, due to the building up of the warp on the beam, arm 14 will move in the same direction since the toggle linkage, in its normal off-center position, forms a rigid connection between arms 10 and 14.

The purpose of the toggle linkage is to swing arm 10 in a counter-clockwise direction while at

the same time arm 14 remains stationary when joint 16 is moved from position 15b to 15a. In this way the pressure roll 8 is moved away from the surface of the beam. The movement of the toggle linkage is accomplished by means of an armature core 21a joined at 16a to rod 21 which in turn is connected at one end to the center joint 16 of the toggle linkage. The armature extends upward through an opening in the solenoid supporting frame 22 fastened to the arm 14, and into the solenoid 23. When the solenoid 23 is energized, the rod 21 is pulled upward carrying the toggle linkage up past its center position thus swinging arm 10 in a counter-clockwise direction lifting pressure roll 8 off the yarn surface of the beam. If desired, a similar solenoid setup may be employed on the other side of the machine. When the toggle linkage moves upward, the tension spring 17 is extended. The mechanism is now in the position shown in Figure 1. When the solenoid is deenergized, the tension spring 17 returns the toggle linkage to its normal position and the pressure roll is returned in contact with the yarn surface on the beam. This position is shown by the dotted lines in Figure 1.

The solenoid is energized whenever a break occurs in the yarns coming from the creel or an extreme loss of tension in the yarn occurs, or the brakes are applied to the beam. Each yarn coming from the creel passes over a dropwire-switch, one of which is shown at 4. The yarn holds the dropwire-switch in such a manner that the circuit to the brakes and solenoid is open and the circuit to the beam driving motor 7 is closed. When a yarn breaks the switch 4 drops and opens the circuit to motor 7 thus stopping the driving means to the beam. The circuit to the solenoid 23 and torque motor 24 is closed. The solenoid is energized immediately and lifts the pressure roll off the beam before the torque motor can brake the beam. The torque motor 24 and solenoid 23 are easily synchronized to operate in this fashion.

When the torque motor 24 is started, it rotates a gear sector 25 in a counter-clockwise direction. The gear sector 25 is secured to or is an integral part of the lever 26 pivoted at 27. The lever 26 is pivotally connected to the link 28, the opposite end of which is secured to the shaft 29 rotatably mounted on the frame of the beamer. At one end of the shaft 30 on which the beam 5 rotates is a brake drum 31 encircling which is the usual brake lining 32. Pivotally mounted on the brake drum 31 at 35 are brake shoes 33 and 34. A bolt 36 with a head 37 and nut 38 extends through the brake shoe extensions 39 and 40 and through a compression spring 41 positioned between the nut 38 and brake shoe extension 40. The compression spring tends to hold the brake shoes tightly about the braking drum, i. e., in braking position.

Positioned between the brake shoe extensions 39 and 40 is a cam-like spreader 42 rigidly fastened to shaft 29. In Figure 1, the apparatus is in the braking position. During the winding operation, the spreader 42 would be in a position approximately 90° in a clockwise direction from that shown, which, of course, would spread the brake shoes and release the brake on the beam. This normal or non-braking position is attained by means of the tension spring 43 extending between the gear sector 25 and the beamer frame. As of necessity, the force of the tension spring 43 is greater than that of the compression or braking spring 41.

When, as previously recited, the torque motor 24 rotates the gear sector 25 in a counter-clockwise direction until the sector touches the fixed stop 25a, the link 28 is moved upwardly thus rotating the shaft 29 and the spreader 42 thereon in a counter-clockwise direction to the position shown. The brake shoes are thus pushed together tightly about the brake drum 31 due to the action of the compression spring 41. Prior to this braking action, the solenoid has been energized lifting the pressure roll from the yarn surface before the beam has started to slow down. All this action takes place in a relatively short period of time thus stopping the beam quickly and efficiently when a break in the yarn occurs without any danger of damage to the yarn on the beam.

Irrespective of the pressure roll retracting and beam braking mechanisms, the lever 10 supporting the pressure roll 8 is rotated in a counter-clockwise direction due to the building up of the warp yarn on the beam. In addition to the lever 10, the arm 14 and sector gear 11 are also rotated in a counter-clockwise direction since the toggle linkage when in position 15b rigidly connects arms 10 and 14 and arm 14 and sector gear 11 are locked to shaft 9 and thus fixed with respect to each other. Thus the entire structure connected to the pressure roll swings to the left as viewed in Figure 1.

When the arm 14 swings to the left, the bar 44 pivotally mounted on the end of arm 14 at 45, is also moved to the left through the snubber mechanism 46. The snubber, described hereinafter, will allow the bar 44 to move to the left but not to the right. Therefore, as the yarn is wound on the beam, the pressure roll support will rotate counter-clockwise moving the bar 44 to the left, and should a high spot or bulge come in contact with the pressure roll moving it farther to the left than the remaining yarn surface on the beam ordinarily would, the snubber 46 prevents bar 44 from moving back to the right thus in turn preventing the pressure roll 8 from returning to make contact with the normal yarn surface on the beam. The pressure roll will not again come in contact with the entire yarn surface on the beam until the overall surface of the beam has reached a radius equal to that of the high spot. Thus an even and perfectly round section beam is assured.

When a beam has been finished and removed from the beamer, it is of course necessary to return the pressure roll to the surface of the new unwound beam. This is accomplished by releasing the snubber, the mechanism for which is described hereinafter, and rotating the sector gear 11 in a clockwise direction by means of the pinion 47 fastened to the fixed transverse shaft 48. It is to be understood that a like pinion and sector gear may be positioned on the opposite side of the beamer in connection with a duplicate mechanism attached to the opposite end of the pressure roll 8 from that viewed in Figure 1.

Attached to the beamer frame by means of bearing-like pieces 49 and 50 is a rotatable shaft 51 attached to the lower end of which is a bevel gear 52 enmeshed with bevel gear 53 fixed on shaft 48. At the other end of shaft 51 is a hand wheel 54. The shaft 51 is attached to the opposite side of the beamer frame from that shown in Figure 1. When the hand wheel 54 is rotated in a counter-clockwise direction, the shaft 48 and pinion 47 are likewise rotated in a counter-

clockwise direction, due to the action of the bevel gears 52 and 53, thus moving the pressure roll supporting structure to the right. In this way, the pressure roll is returned to its starting position ready for the winding of a new warp beam. If desired, the shaft 51 may be rotated by means of a motor or the like, instead of manually.

For a description of the snubber 46 and the snubber releasing means, reference should be made to Figures 1 and 3. The bars 44 extend through the snubber housings 55 which are pivotally mounted on conical pins 56 fastened to supporting members 57, which in turn are mounted on the angle iron 58 mounted transversely in the beamer frame. The snubber housings are pivotally mounted to allow for the slight up and downward movement imparted to bar 44 as a result of the rotation of arms 14 and 11 about the pivotal point 12.

Pivotally mounted in the center of the snubber housing 55 on the shaft 59 is a one-way friction device or block 60, the underside of which is made to conform to the shape of bar 44 on which it rests. The bar 44 may be any shape but that illustrated is preferred in which the sides 61 and 62 slope inwardly and upwardly. The block 60 is held down tightly against the bar 44 by means of the compression spring 63 which is adjustably mounted on the plate 64 extending transverse of the snubber housing and fastened to the sides thereof. The tension on the spring is adjusted by means of the screw 65 and lock nut 66. When the bar 44 moves to the left, as viewed in Figure 1, the block 60 is swung about the pivot 59 in a clockwise direction against the force of the spring 63, thus permitting the bar 44 to pass through the snubber housing. When an attempt is made to move the bar 44 to the right, the force is against the pivot 59 thus binding the block or snubber 60 and the bar 44 and preventing any movement of the latter through the snubber housing. Hence, a snubber releasing mechanism is necessary in order to return the pressure roll to its starting position.

The snubber releasing mechanism comprises a steel cable 67 fastened to one side of the beamer frame by means of a tension spring 68 and extending transverse of the beamer over the snubber housings and over a pulley 69 fastened to the opposite side of the beamer frame. The cable then extends down under pulley 70, along the base of the beamer and under pulley 71, up over pulley 72, and down to a foot pedal 73 where it is fastened. Extending outwardly from the non-pivotal ends of the snubbers or blocks 60 are pins 74. These pins extend out over the wedge-shaped members 75 fastened to the cable 67. The wedge-shaped members 75 slope downwardly from right to left as viewed in Figure 3 and are positioned between the pins 74 and the upper surfaces 76 and 77 of the snubber housing sides. When the foot pedal 73 is pressed down the cable moves from right to left, as viewed in Figure 3, against the action of spring 68. The wedges 75 passing under the pins 74 raise the same thus rotating the snubbers about the pivots 59 and removing them from contact with the bars 44 permitting the movement of the latter in either direction. When the pressure on the foot pedal is released, the tension spring 68 restores the cable to its starting position thus removing the wedges 75 from contact with the pins 74. In order to limit the movement of the cable and protect the spring, metal stops 78 and

19 are fastened to the cable on either side of the snubber housing.

In Figure 2 there is shown another embodiment of the invention wherein the pressure roll 8 is moved away from the yarn surface on the beam by means of a cable 80 fastened at one end to the center joint 16 of the toggle linkage and extending down around the link 11 and fastened to a pulley 81 on the torque motor 24. When the pressure roll is against the surface of the beam, the toggle linkage is in the dotted line position 82 with its center slightly above the straight line between pivotal points 19 and 20 on arms 14 and 10 respectively, and resting against the toggle stops 83 and 84 on arms 14 and 10. If a yarn breaks or the manual switch is closed, the torque motor 24 is actuated pulling the cable 80 which in turn pulls the toggle linkage down through the center position to the position shown thus raising the arm 10 and the pressure roll 8 from the yarn surface on the beam. The toggle linkage acts against the compression spring 35 which is fastened to the arm 10. The purpose of the compression spring is to return the pressure roll to the surface of the yarn on the beam when the circuit to the torque motor 24 is broken.

There may be a similar set-up on the other side of the beamer with both cables connected to the one torque motor. The gears on the torque motor are so chosen that the pressure roll lifts off the beam before the brake is applied to the beam.

Since the braking mechanism, snubber, snubber release, etc. are the same in this embodiment as that shown in Figure 1, a description of the same is not necessary here and is not shown in Figure 2 for the purpose of simplicity.

Figure 4 is a diagrammatic view of an electrical system that may be employed in connection with the embodiment shown in Figures 1 and 2. As shown, the circuit to the beam drive motor 7 is closed. Line 86 runs from the power supply 87 to the terminal 88 on motor 7. Line 89 runs from the power supply, through the drop-switch 90, the holding coil 90a of which is deenergized as shown, to the terminal 91 on motor 7.

The torque motor 24 is connected to the power supply by line 92 connected to terminal 93 on the motor and line 94, which runs from terminal 95 on motor 24 through a manual switch 103, then through a holding coil 102 about the lower end of drop-switch 90. The upper half of the lower end of drop-switch 90, below the contact bar 104, is made of non-magnetic material so that in order to center the drop-switch in coil 102 when it is energized the switch 90 must be raised thus closing the line 94 by means of contact 104. The circuit is completed through line 89 when the switch 90 is energized.

The solenoids 23 are connected in parallel with the torque motor 24 by means of lines 96 and 97 running off from lines 92 and 94 respectively.

At 98 there is a holding coil circuit which is in series or in parallel with a holding coil of a conventional starting system (not shown) for the beam drive motor 7. As shown, when the drive motor has been started, the coil 98 is energized lifting the drop-switch 99 closing the line 100 running from the power supply to the holding coil 90a of drop-switch 90. However, the coil 90a is not energized when the drive motor 7 is running because the other line 101 between the power supply and the coil 90a is broken by reason of the drop-switch 4 being raised by the yarn 4. Line 104 is connected in series with a number of

drop-switches 4, there being one for each yarn or thread being wound on the beam.

When one of the yarns 4 breaks, the drop-switch 4 falls closing the circuit to the holding coil 90a which is energized lifting the drop-switch 99. This breaks the circuit to the beam drive motor 7 stopping the same. The holding coil 98 is then deenergized as a result allowing the drop-switch 99 to break line 100 and this line 10 will not again be closed until the holding coil 98 is again energized by restarting the drive motor 7. When the switch 90 is raised, contact bar 104 closes the circuit to the solenoids 23 energizing the same and lifting the pressure roll from the yarn surface on the beam. At the same time, the torque motor 24 is started applying the brakes to the beam. The circuit to the solenoids and torque motor is kept closed by reason of the holding coil 102 being energized holding contact 104 up in line 94. This is necessary since holding coil 90a has become deenergized by reason of the break in line 100 due to the deenergization of holding coil 98 which occurred when the circuit to the beam driving motor 7 was broken.

25 The torque motor will continue running and the solenoids remain energized until the circuit is broken. This is accomplished by means of the manual switch 103. The torque motor stops releasing the brakes on the beam, and the solenoids 30 are deenergized allowing the pressure roll to return to the yarn surface. Switch 103 is then closed but the torque motor cannot start since the drop-switch 90 has opened line 94 and closed line 89 when the holding coil 102 was deenergized.

35 The driving motor 7 will not function until restarted by the starting system (not shown) which was thrown out when the motor 7 stopped.

The electrical system employed with the embodiment shown in Figure 2 may be the same as that shown in Figure 4 with the exception that the solenoids 23 are eliminated.

The present invention is applicable to the winding of any type yarn on a warp beam, such as cotton, wool, silk, rayon, cellulose acetate yarn, 45 nylon, vinyon, and the like, or to winding of fabrics, paper, sheet material, films such as cellophane, cellulose ethers and esters, and the like, etc.

By means of the present invention, a round 50 cross-section beam or winding may be obtained and the same stopped during winding thereof without danger of damage to the wound material due to friction between the pressure roll and winding roll while the latter is being stopped. 55 Further, a uniform pressure on the windings is assured throughout the entire winding operation.

It is to be understood that changes and variations may be made without departing from the spirit and scope of the invention as defined in the appended claims.

We claim:

1. An apparatus for winding comprising a rotatable driven warp beam for receiving a winding thereabout, lever means mounted pivotally 65 about an axis outside the periphery of the warp beam; a rotatable pressure roll adjacent said beam; pressure roll supporting means, said supporting means being pivotally mounted on the lever means, toggle linkage connecting the pressure roll supporting means to the lever means and normally holding them in fixed relative position, means for preventing relative movement of the pressure roll and beam toward each other during displacement of the lever means, and 70 pressure roll assembly as a unit about said pivotal 75 pressure roll assembly.

axis by virtue of increasing diameter of winding on the rotatable driven beam, braking means connected to the rotatable driven beam, and means responsive to the actuation of the braking means for actuating the toggle linkage means to swing the pressure roll mounting relative to the lever means to remove the pressure roll from the winding.

2. An apparatus as defined in claim 1 wherein the means for preventing relative movement of the pressure roll and beam toward each other during displacement by virtue of increasing diameter of winding on the rotatable driven beam is a one way snubbing means.

3. An apparatus as defined in claim 1 wherein the means responsive to the actuation of the braking means for actuating the toggle linkage comprises a solenoid connected in parallel with the braking means.

4. An apparatus as defined in claim 1 wherein the means responsive to the actuation of the braking means for actuating the toggle linkage comprises a cable connecting the braking means and the toggle linkage.

5. An apparatus for winding comprising a rotatable element for receiving a winding thereabout, a rotatable pressure roll adjacent said element, means for movably mounting the roll, one way snubbing means for preventing relative movement of the roll and element toward each other during displacement by virtue of increasing diameter of winding on the rotatable element comprising a rod and friction means, said rod being connected to the roll mounting means and making sliding contact with the friction means, braking means connected to the rotatable element, retracting means for moving the pressure roll to and from the surface of the winding on the element, and means responsive to the actuation of the braking means for actuating the retracting means to remove the roll from the winding.

6. An apparatus for winding comprising a rotatable element for receiving a winding thereabout, a rotatable pressure roll adjacent said element, means for mounting the roll pivotally about an axis outside its periphery, one way snubbing means for preventing relative movement of the roll and element toward each other during displacement by virtue of increasing diameter of winding on the rotatable element comprising a rod and friction means, said rod being connected to the roll mounting means and making sliding contact with the friction means, braking means connected to the rotatable element, retracting means for moving the pressure roll to and from the surface of the winding on the element, and means responsive to the actuation of the braking means for actuating the retracting means to remove the roll from the winding.

7. An apparatus for winding comprising a rotatable driven warp beam for receiving a winding thereabout, a rotatable pressure roll adjacent said beam, means for movably mounting the pressure roll, one way snubbing means for preventing relative movement of the pressure roll and beam toward each other during displacement by virtue of increasing diameter of winding on the rotatable driven beam comprising a rod and friction means, said rod being connected to the roll mounting means and making sliding contact with the friction means, braking means connected to the rotatable driven beam, retracting means for moving the pressure roll

to and from the surface of the winding on the beam, and means responsive to the actuation of the braking means for actuating the retracting means to remove the pressure roll from the winding.

8. An apparatus for winding comprising a rotatable driven warp beam for receiving a winding thereabout, a rotatable pressure roll adjacent said beam, means for mounting the pressure roll pivotally about an axis outside its periphery, one way snubbing means for preventing relative movement of the pressure roll and beam toward each other during displacement by virtue of increasing diameter of winding on the rotatable driven beam comprising a rod and friction means, said rod being connected to the roll mounting means and making sliding contact with the friction means, braking means connected to the rotatable driven beam, retracting means for moving the pressure roll to and from the surface of the winding on the beam, and means responsive to the actuation of the braking means for actuating the retracting means to remove the pressure roll from the winding.

9. An apparatus for winding comprising a rotatable element for receiving a winding thereabout, a rotatable pressure roll adjacent said element, lever means mounted pivotally about an axis outside the periphery of the element, means for mounting the pressure roll pivotally on the lever means, one way snubbing means for preventing relative movement of the pressure roll and rotatable element toward each other during displacement by virtue of increasing diameter of winding on the element comprising a rod and friction means, said rod being connected to the roll mounting means and making sliding contact with the friction means, braking means connected to the rotatable element, retracting means for moving the pressure roll to and from the surface of the winding on the element, and means responsive to the actuation of the braking means for actuating the retracting means to remove the pressure roll from the winding.

10. An apparatus for winding comprising a rotatable driven warp beam for receiving a winding thereabout, a rotatable pressure roll adjacent said beam, lever means mounted pivotally about an axis outside the periphery of the beam, means for mounting the pressure roll pivotally on the lever means, one way snubbing means for preventing relative movement of the pressure roll and rotatable beam toward each other during displacement by virtue of increasing diameter of winding on the beam comprising a rod and friction means, said rod being connected to the roll mounting means and making sliding contact with the friction means, braking means connected to the rotatable driven beam, retracting means for moving the pressure roll to and from the surface of the winding on the beam, and means responsive to the actuation of the braking means for actuating the retracting means to remove the pressure roll from the winding.

11. An apparatus as defined in claim 2 wherein the one way snubbing means comprises a rod and friction means, said rod being connected to the lever means and making sliding contact with the friction means.

12. An apparatus as defined in claim 2 wherein the one way snubbing means comprises a housing, a pivotally mounted block in said housing, a rod slidably mounted in the housing and in frictional engagement with the block, said rod

being connected to the lever means, and resilient means for forcing the block into frictional engagement with the rod.

13. An apparatus for winding comprising a rotatable driven warp beam for receiving a winding thereabout, lever means mounted pivotally about an axis outside the periphery of the warp beam, a rotatable pressure roll adjacent said beam, means for mounting the pressure roll pivotally on the lever means, toggle linkage connecting the pressure roll mounting and lever means and normally holding them in fixed relative position, one way snubbing means for preventing relative movement of the pressure roll and beam toward each other during displacement of the lever means and pressure roll assembly as a unit about said pivotal axis by virtue of increasing diameter of winding on the rotatable driven beam, braking means connected to the rotatable driven beam, and solenoid means connected in parallel with the braking means, said solenoid means being responsive to the actuation of the braking means for actuating the toggle linkage means to swing the pressure roll mounting relative to the lever means to remove the pressure roll from the winding.

14. An apparatus as defined in claim 13 wherein the one way snubbing means comprises a rod and friction means, said rod being connected to the lever means and making sliding contact with the friction means.

15. An apparatus for winding comprising a rotatable driven warp beam for receiving a winding thereabout, lever means mounted pivotally about an axis outside the periphery of the warp beam, a rotatable pressure roll adjacent said beam, means for mounting the pressure roll pivotally on the lever means, toggle linkage connecting the pressure roll mounting and lever means and normally holding them in fixed relative position, one way snubbing means for preventing relative movement of the pressure roll and beam toward each other during displacement of the lever means and pressure roll assembly as a unit about said pivotal axis by virtue of increasing diameter of winding on the rotatable driven beam, braking means connected to the rotatable driven beam, and cable means connected between the braking means and the toggle linkage, said cable means being responsive to the actuation of the braking means for actuating the toggle linkage means to swing the pressure roll mounting relative to the lever means to remove the pressure roll from the winding.

16. An apparatus as defined in claim 15 where-

in the one way snubbing means comprises a rod and friction means, said rod being connected to the lever means and making sliding contact with the friction means.

5 17. An apparatus for winding comprising a rotatable element for receiving a winding thereabout, pivotally mounted lever means, a rotatable pressure roll adjacent said element, pressure roll supporting means, said supporting means being 10 pivotally mounted on the lever means, toggle linkage connecting the pressure roll supporting means to the lever means and normally holding them in fixed relative position, means for preventing relative movement of the pressure roll 15 and element toward each other during displacement of the lever means and pressure roll assembly as a unit about the axis of the pivotally mounted lever means by virtue of increasing diameter of winding on the rotatable element, braking means connected to the rotatable element, and means responsive to the actuation of the braking means for actuating the toggle linkage to swing the pressure roll mounting relative to the lever means to remove the pressure roll from the winding.

18. An apparatus for winding comprising a rotatable element for receiving a winding thereabout, a pivotally mounted lever, a rotatable pressure roll adjacent said element, a second lever 30 for supporting the pressure roll and pivotally connected to the first lever, toggle linkage connecting the first lever with the second lever and normally holding them in fixed relative position, means for preventing relative movement of the 35 pressure roll and element toward each other during displacement of the first lever and pressure roll by virtue of increasing diameter of winding on the rotatable element, braking means connected to the rotatable element, and means responsive to the actuation of the braking means for actuating the toggle linkage to swing the pressure roll relative to the first lever to remove the pressure roll from the winding.
